[57] ABSTRACT

Diolefins, present in minor amounts, in gaseous feed streams, particularly those to be used in alkylation reactions are selectively converted to mono-olefins by hydrogenation over sulfided nickel-tungsten catalyst.

SELECTIVE HYDROGENATION OF DIOLEFINS

BACKGROUND OF THE INVENTION

This invention relates to the selective hydrogenation of diolefins in hydrocarbon streams containing mono-olefins and is especially concerned with selective conversion of propadiene and butadiene contaminants in propylene and butene charge stocks employed in alkylation process for the production of aviation and motor gasoline wherein the feed stock is contaminated with sulfur. It is also useful for the selective conversion of C_4 diolefins to mono-olefins, e.g. butadienes to butenes.

The C_3/C_4 fraction employed in alkylation processes is principally that obtained from thermal or catalytic cracking of higher boiling hydrocarbons or from a hydrocarbon coking operation; the C_3/C_4 cut is taken over a practical boiling range so as to be substantially free of C_5 hydrocarbons, although minor amounts of these may be present by entrainment or otherwise. Such C_3/C_4 fraction may generally contain in the order of about 0.3 percent and up to about 2 percent or more by weight of diolefin; the C_3/C_4 fraction from a cracking operation rarely contains as much as 2 percent of diolefin. Even this small content of diolefin in the feed for the alkylation process has been widely recognized as being extremely undesirable for the one reason, among others, of the greatly increased consumption of acid made necessary thereby, as a result of forming tarry acid-diolefin condensation products, adversely affecting the over-all economics of the alkylation process. Several suggestions for the conversion or removal of the diolefins from hydrocarbon mixtures also containing mono-olefins have not proved attractive, because of accompanying concomitant disproportionate loss of mono-olefins in the treated product, and high operating and investment costs.

In the case of a C_3/C_4 fraction derived from a coking operation which may contain even higher proportions of diolefins, going up to 5 percent or more, the problem is even more acute, and the use of such fractions for alkylation has been largely avoided.

Among the suggestions made to overcome the above difficulties is the proposal made in U.S. Pat. No. 3,113,983 to Kirsch et al., issued Dec. 10, 1963, wherein diolefin contaminants are selectively hydrogenated to olefins in an alkylation feed by passage of the feed over a sulfided cobalt molybdenum catalyst supported on Al_2O_3 . Unfortunately the use of such catalysts has several drawbacks.

1. Relatively high operating severity is required (pressure 200-400 psig, temperatures higher than 400° F.).
2. To maintain the catalyst activity at the desired level, high hydrogen to diolefin ratios are required.
3. Hydrogenation unit effluent usually requires an intermediate H_2 /hydrocarbon separation step. Alkylation reactions are carried out in liquid phase. Presence of substantial amount of H_2 would hamper (or even render impractical) the liquefaction of the reactants by steps which usually involve low temperature operations (refrigeration).
4. Co-Mo catalyst does not display the same degree of selectivity for diolefin conversion as the proposed Ni-W catalyst.

Supported nickel and palladium catalysts are excellent hydrogenation catalysts in the diolefin conversion service. However, they display very low tolerance of sulfur in the fresh diolefin feed. Consequently, their use is limited to sulfur-free feedstocks.

SUMMARY OF THE INVENTION

In accordance with the present invention, the selective conversion of diolefins to olefins, particularly in feed stocks containing sulfur, is accomplished by effecting the hydrogenation over a catalyst comprising sulfided nickel-tungsten on an inert support such as alumina, kieselguhr, silica-free clay, bauxite, mullite, etc., alumina being preferred.

DETAILED DESCRIPTION

The process of the invention involves passing a hydrocarbon stream containing minor amounts of diolefins and sulfur over a sulfided nickel-tungsten catalyst on alumina or other support. A C_3/C_4 stream is of particular interest in this connection.

The catalyst contains 4 to 6 wt. percent nickel, 14 to 20 wt. percent tungsten and the balance Al_2O_3 . The tungsten to nickel ratio is preferably 4/1 to 5/1. The catalyst is sulfided with H_2S or CS_2 to prior to use.

The above catalyst has been found to have a remarkable degree of selectivity in that it is active for the hydrogenation of diolefins to monoolefins but relatively inactive for the hydrogenation of mono-olefins to paraffins in the temperature range of 200°-400° F., pressure 150-200 psig and hydrogen/diolefin ratio of 1/1 to 6.1.

While the greatest advantages of the described process are obtained in the treatment of olefinic C_3/C_4 hydrocarbon streams containing about 2 percent butadiene by weight of total hydrocarbons, the process is also applicable, but not necessarily with equal results, to the treatment of olefinic C_3/C_4 fractions of higher diolefin content, such as a butane-butylene fraction obtained from a thermal coking operation which may include up to about 5-6 percent diolefins. A further application of the invention lies in the treatment of a butylene-rich stream from a dehydrogenation process containing from a fraction of a percent up to about 5 percent diolefin. For example, in the dehydrogenation of butane, for production of butadiene, particularly after separation of the product butadiene by fractionation and extraction, there still remains in the monoolefin-rich raffinate a small percentage of butadiene of from about a fraction of a percent up to about 2 percent depending upon the efficiency of the separation. This small amount of butadiene cannot be economically recovered as such, and interferes with the possible uses of the raffinate, for instance as feed to alkylation. Some butadiene is also produced in those processes designed principally for conversion of butane to butene. If the quantity of butadiene in the product is sufficiently great, say in excess of about 5 percent its recovery by known procedures may be warranted.

Smaller quantities of butadiene, as between about 3 to 5 percent may or may not be worth recovering as such, depending upon recovery costs versus market demand and value. In either of the above instances, the enhancement of the butene product by selective hydrogenation of diolefins in accordance with the present invention, comes into consideration.

The selective hydrogenation of propadiene/butadiene in a mono-olefin-rich mixture by the present invention is more easily accomplished and with greatest efficiency when the proportion of diolefin in the mixture is quite low, for example about 2 percent. In such instance catalytic hydrogenation under the described operating conditions can be accomplished in isothermal or adiabatic reactor systems, and some variation from the optimum in process variables can be tolerated at the expense of some sacrifice in yield and purity of product.

To illustrate the benefits of the invention, feeds having the following composition

When the above experiment was duplicated on a commercial scale using a feed containing 0-4 mol. percent of butadiene, essentially complete removal of 1,3-butadiene was achieved.

I claim:

1. A process for selectively hydrogenating diolefins into their corresponding monoolefins which comprises passing a sulfur-containing feed stream containing monoolefins and less than 6 percent diolefins together with hydrogen over a supported sulfided nickel-tungsten catalyst comprising 4 to 6 weight percent nickel and 14 to 20 weight percent tungsten at a temperature in the range of 200°-400° F., a pressure in the range of 150-200 psig and a hydrogen to diolefin ratio of 1/1 to 6/1.

2. The process of claim 1 in which the feed stream contains C₃ and C₄ diolefins.

3. The process of claim 1 in which the diolefin content of the feed stream is less than 2 percent.

4. The process of claim 1 in which the tungsten-to-nickel ratio is said catalyst is between about 4/1 to 5/1.
